(57) **CLAIM**

The ornamental design for a beverage container, as shown and described.

DESCRIPTION

FIG. 1 is a front view of a beverage container showing our new design;

FIG. 2 is a bottom view thereof;

FIG. 3 is a top view thereof; and,

FIG. 4 is a side view thereof.

The sides not shown or described in the specification form no part of the claimed design.

The broken line showing of the fitment is included for the purpose of illustrating portions of the beverage container and forms no part of the claimed design.

1 Claim, 2 Drawing Sheets***FIG. 1***

FIG. 2

FIG. 3

FIG. 4
